UNITED STATES PATENT OFFICE

151,231

DESIGN FOR A GAME BOARD

John E. Funderburg, Ashland, Ky.

Application April 29, 1947, Serial No. 138,680

Term of patent 14 years

(Cl. D34—5)

To all whom it may concern:

Be it known that I, John E. Funderburg, a citizen of the United States, residing at Ashland, in the county of Boyd and State of Kentucky, have invented a new, original, and ornamental Design for a Game Board, of which the following is a specification, reference being had to the accompanying drawings, forming part thereof.

I claim:

The ornamental design for a game board, as shown.

JOHN E. FUNDERBURG.
